UNITED STATES PATENT OFFICE.

GEORGE EDWARD JOHN OAKLEY, OF SLOUGH, AND KENNETH GRAHAM SMITH, OF MAIDENHEAD, ENGLAND, ASSIGNORS TO BRANDES LABORATORIES, INC., OF NEWARK, NEW JERSEY, A CORPORATION OF NEW JERSEY.

RADIO RECEIVING APPARATUS.

Application, filed December 2, 1926. Serial No. 152,197.

Our invention relates broadly to radio receiving apparatus and more particularly to apparatus for tuning a radio receiver to selected signaling frequencies.

5 One of the objects of our invention is to provide a tuning apparatus for radio receivers which is effective over the broadcast range of signaling frequencies and also effective at a signaling frequency which is 10 widely separated from the broadcast range of frequencies.

Another object of our invention is to provide a tuning apparatus by which a radio receiver may be adjusted to respond to a plurality of frequencies within a selected band 15 of frequencies and selectively respond to a definite frequency which is removed in the frequency scale from the aforementioned band of frequencies.

20 Still another object of our invention is to provide a construction of tuning apparatus whereby the coupling between a radio frequency energy collecting circuit and a radio receiving circuit may be modified for enabling the receiver to operate over a selected 25 band of frequencies or to respond to a definite frequency substantially removed from the band of frequencies.

Our invention is directed to a receiving apparatus in which regenerative amplification 30 is secured in an electron tube circuit system with separate inductance elements arranged to be effectively included in the radio frequency energy collecting circuit with which a reaction coil of the regenerative amplification 35 system may be selectively associated with either of the inductance elements for securing response over a selected band of frequencies or at a frequency which is widely 40 separated from the selected band of frequencies.

Our invention will be more fully understood from the specification hereinafter following by reference to the accompanying 45 drawings in which:

Figure 1 is a side elevation of the reaction coil mounting for the tuning apparatus of our invention; Fig. 2 is a view taken on line 3—3 of Fig. 1 showing a part of the 50 reaction coil mounting in cross-section.

The receiving apparatus of our invention has been developed to meet the requirements of the law, whereby a broadcast radio receiver may be responsive to signals of long

wave length while the same receiver is useful for broadcast radio reception over a selected band of frequencies.

Tuning condenser 4 is shown in circuit with the antenna 3, the antenna connecting to the grid circuit of the electron tube 1 through the grid condenser and high resistance path 12. Tuning condenser 11 is arranged across the input circuit. The three-way inductance comprises windings 5, 9 and 10. The winding 5 responds to long waves and is denoted as the Daventry coil B in Figs. 2 and 3. The winding 9 responds to short wave lengths and is designated as coil A in Figs. 2 and 3. The reaction coil 10 is designated at C in Figs. 2 and 3 as supported on a frame 29 which may be swung in an arc upon the support 28 extending from arms 27 under control of the shaft member 26 which is journaled at 24 and 25 in the side portions 22 of the three-way coil mounting. Switching devices 6 and 8 are provided for effectively including a selected one of the windings 5 or 9 in the receiving circuit. The receiving circuit is connected to ground as represented at 7. The output circuit of the detector tube 1 includes the reaction coil 10 and the primary winding 15 of the audio frequency transformer 14, the secondary winding 16 of which connects to the input circuit of the amplifier tube 2.

In order to place a proper bias potential upon the grid of the amplifier tube 2 a battery 19 under control of rheostat 20 is arranged in the input circuit of the tube 2. The high potential for the output circuit of tube 1 and the output circuit for tube 2 are obtained from battery source 18 with terminal 17 leading to the telephone or loud speaker circuit. A battery 21 is provided for heating the cathodes of the tubes 1 and 2.

Referring to Fig. 1 of the drawings the coil A constituted by the short wave winding 9 is supported from the mounting 22 by means of lateral plate 23 while coil B constituted by the long wave winding 5 is mounted from the laterally extending plate portion 24 in an axis which is normal to the axis of the winding 9. The reaction coil 10 designated at C may swing about a pivot with the shaft 26 as an axis to permit the coupling of reaction coil 10 with winding 9 or the independent coupling of reaction coil 10 with the winding 5.

Winding 9 or short wave coil A is connected in circuit and rendered effective by the closing of contacts connected with the coil. Reaction winding 10 designated at coil 5 C is swung near to coil A as shown in Fig. 1 for the securing of regenerative effect. When long wave length signals are to be received the short wave coil 9 is disconnected from the tuning circuit and the long wave coil 5 is effectively connected in the tuning circuit by the closing of another set of contacts and then the reaction coil C is swung towards the short wave coil B and regenerative action secured by the coupled relationship of windings 10 and 5. The influence of electromagnetic and electrostatic effects of windings 5 and 9 with respect to each other is substantially eliminated by means of the mounting of the windings in axes which are normal to each other. When coil 10 is inductively coupled with coil 9 the coil 5 is substantially inert and when winding 10 is inductively coupled to winding 5 the winding 9 is substantially inert.

25 The structure of tuning apparatus illustrated herein has been found to be very practical in its operation, and while we have described a preferred embodiment of the invention, we desire that it be understood that 30 modifications may be made and that no limitations upon the invention are intended other than are imposed by the scope of the appended claims.

What we claim as new and desire to secure 35 by Letters Patent of the United States is as follows:

1. Tuning apparatus comprising a frame structure constituted by a pair of side members interconnected by laterally extending 40 members disposed in planes at right angles one to the other, each of said laterally extending members serving to support separate inductance units with their axes normal one to the other and a separate coil member 45 pivotally mounted in said frame and being arranged to be swung into coupled relation-

ship with a selected one of said aforementioned inductance units.

2. Tuning apparatus for radio receiving systems comprising a frame constituted by 50 a pair of side members, laterally extending members disposed between said side members and in planes substantially at an angle with respect to each other, said laterally extending members providing means for supporting a pair of independent inductance coils with their axes substantially normal one to the other, a rotatable shaft member journaled adjacent opposite ends thereof in said side members, said rotatable shaft member 55 carrying an inductance coil arranged to fit concentrically within each of said aforementioned inductance coils whereby said last mentioned inductance coil may be independently coupled with a selected one of said 60 aforementioned inductance coils.

3: Tuning apparatus comprising a frame structure constituted by a pair of side members, laterally extending members interconnecting said side members, cylindrical coil 70 supports carried by each of said laterally extending members with the axes of said supports disposed substantially normal one to the other, windings carried by said coil supports, a rotatable shaft member journaled adjacent opposite ends thereof in said side members in a position between said aforementioned coil supports, a separate coil support carried by said rotatable shaft member, and an independent winding on said 75 separate coil support arranged in such manner that said separate coil support may be positioned concentrically within a selected one of said first mentioned coil supports for establishing a coupled relationship between 80 said independent winding and a selected one of the windings carried by said first mentioned coil supports.

In testimony whereof we affix our signatures.

GEORGE EDWARD JOHN OAKLEY.
KENNETH GRAHAM SMITH.
